UNITED STATES PATENT OFFICE.

CHARLES A. HAISLEY, OF RICHMOND, INDIANA.

AUTOMOBILE LOCK.

Application filed May 15, 1922. Serial No. 500,911.

To all whom it may concern:

Be it known that I, CHARLES A. HAISLEY, a citizen of the United States, residing at Richmond, in the county of Wayne, State 5 of Indiana, have invented a new and useful Automobile Lock, of which the following is a full, clear, and comprehensive specification and exposition, the same being such as will enable others to make and use the 10 same with exactitude.

The object of this present invention, broadly stated, is to provide means for intentionally preventing the functioning of motors, especially the motors of automobiles, 15 but still permitting the motor to be operated by an authorized person when desired.

More particularly stated, my object is to provide means whereby the custodian of an automobile or the like may close and lock 20 the exhaust, thereby preventing the operation of the motor by an unauthorized person, as it is well known that a motor can not function if the exhaust be closed.

Other objects and particular advantages 25 of the invention will be brought out in the course of the following description, and that which is new will be correlated in the claim.

The preferred means for carrying out the principles of my invention in a practical 30 and an efficient manner is shown in the accompanying drawings, in which—Figure 1 is a side elevation of my construction as attached in operative condition in connection with the exhaust manifold of a motor. Figure 2 is a plan view of the same. Figure 3 is a central sectional view taken 35 through my device. Figure 4 is a detail edge view of the valve shutter and a portion of its stem. Figure 5 is a plan view 40 of the upper disc alone. Figure 6 is a plan view of the lower disc alone. And Figure 7 is a side elevation of the discharge end portion of an exhaust manifold prior to the installation of my invention therewith.

Similar indices denote like parts throughout the several views. In order that the construction, the operation, and the advantages of my invention may be more fully understood and appreciated, I will now take 45 up a detailed description thereof, in which I will set forth the same as fully and clearly as I may.

In the drawings letter A denotes the usual 50 exhaust manifold of an explosion motor, having its discharge end provided with threads α . Letter B denotes the exhaust

pipe leading from the manifold A to the muffler (not shown). Said pipe B is provided with the coupling C, which is adapted to be run on the threads α , as shown. 60

The dotted lines D designate the approximate location of the gear case or some other relatively stationary element. Letter E denotes the toe-board forming a part of the floor of an automobile with which my 65 device is connected. And letter F denotes a pad-lock, or other locking means. All of the above parts are of ordinary construction and they may be variously changed, and are not parts of this invention. 70

My invention proper consists primarily of a butterfly valve, comprising the body portion 1, one end of which is provided with the exterior threads 2 which are adapted to permit the coupling C to be run thereon. 75 The other end of the body 1 is interiorly threaded to receive the threads α .

It, of course, is to be understood that there is a passage-way 3 through the body 1 which corresponds with the passage-ways through 80 the manifold A and the pipe B.

Numerical 4 denotes the valve-stem, which is integral with the body 1, and it projects at right-angles therefrom.

Formed integral with the outer end of the 85 stem 4, and extending out therearound, is the inner disc 5, the same being parallel with the body 1 and the pipe B. Formed through the disc 5, near the periphery thereof, are the two round apertures 6 and 7. 90 Secured in and extending out from the face of the disc 5 is the pin 8.

Numerical 9 denotes the upper or outer disc, it being of the same diameter as the disc 5. A segmental notch 10 is formed in the 95 peripheral portion of one-quarter of the disc 9, as is shown in Fig. 5. Also an aperture 13 is formed through the peripheral portion of the disc 9, which may register with apertures 6—7. Said disc 9 should be 100 formed of very hard metal or the like. A shaft aperture or bearing 11 is formed concentrically through the stem 4 and the disc 5, and a corresponding aperture is formed through the disc 9, to receive the shaft 12, 105 which latter is revolvable in said aperture 11, but the disc 9 is rigidly secured to the shaft 12 whereby it will revolve therewith. Means for turning the shaft 12 manually is provided by the cross-bar 14 which is disposed through the upper end portion of the shaft 12. 110

As shown at 17 in Fig. 3, a bearing aperture is formed through the center of the lower portion of the body 1 in which fits the lower end of the shaft 12.

5 The lower portion of the shaft 12 is split to form the slot 15 which is of the same width as is the thickness of the valve shutter 16 which is located therein. Numerals 18 and 19 denote rivets by which the valve shutter 16 is rigidly secured to the shaft 12.

10 In assembling the device the disc 9 is first secured on the shaft 12 (or it may be integral therewith), the valve shutter 16 is placed in position in the passageway 3. The 15 shaft 12 is then pressed down through the stem 4, striding the valve shutter 16 and with its lower end operative in the bearing 17. The rivets 18-19 are then driven in 20 and riveted to retain the valve shutter in place. Now with the insertion of the cross-bar 14 the device proper will be in assembled condition.

15 In order to place my invention in operative position I first remove the pipe B and 25 the coupling C from the manifold A. I then bring my device to position and cause the threads a to enter the interior threads of the body 1, which by turning the device will cause a tight joint to be formed. I next 30 replace the pipe B by bringing it to the outer (rear) end of the body 1 and run the coupling C on the threads 2. In practice the stem 4 should extend through the toe-board E so that the disc 5 will be thereabove. It 35 is to be understood that my device is to be connected with the manifold A before the device and the manifold are placed in position in the machine, as the device can not be turned after the manifold is secured in 40 place on account of the gear-case D.

45 It is now quite evident that if the valve shutter 16 be turned edgewise in the passageway 3 that the exhaust may pass from the manifold A out through the pipe B as before, this position being shown in Fig. 1, at which time the apertures 13 and 6 will register with each other, permitting the shackle of the lock F to be inserted therethrough.

whereby the device may be locked against being closed.

50 Now desiring to lock the device I first remove the lock F and then by grasping the bar 14 I give the shaft 12 a quarter turn, that is turning the pin 8 from one to the other extreme of the notch 10. This will cause the valve shutter to extend across the passageway 3 thereby preventing the escape of the exhaust therethrough. Then by placing the lock again in securing position, that is inserting its shackle through the apertures 13 and 7, which are then in register with each other, it is evident that the exhaust will be locked and the motor can not be operated until the valve shutter has been turned to open position, thereby accomplishing the desideratum of this invention.

55 Having now fully shown and described my invention, what I claim and desire to secure by Letters Patent of the United States, is—

60 An automobile locking means comprising in combination with an exhaust manifold, a body adapted to be secured to the discharge end of the exhaust manifold with a passageway therethrough forming a continuation of the passageway through the manifold, a stem rotatably mounted in said body and extending out therefrom at right angles thereto, a valve shutter carried by said stem and adapted to be turned in said 65 passageway in the body to open and close said passageway, a disc integral with said body and concentric of the stem, a second disc rigidly connected with said stem and contacting flat with the first disc, there being 70 apertures formed through both of said discs with the apertures of one disc adapted to register with the apertures of the other disc, a padlock whose shackle is adapted to be inserted in two of said apertures when they 75 register with each other, means whereby said stem may be turned manually, and means for limiting the rotation of the stem in either direction, all substantially as shown and described.

70 75 80 85 90 95 CHARLES A. HAISLEY.
